WRAPPING MACHINE

Oscar Sandberg, Grand Rapids, Mich., assignor
to Automatic Packaging Machinery Company,
Grand Rapids, Mich.

Application December 11, 1937, Serial No. 179,260

23 Claims. (Cl. 93—2)

This invention relates to improvements in wrapping machines.

The main objects of my invention are:

First, to provide a wrapping machine adapted to enclose candy bars or other irregularly shaped objects in a wrapper of regular size and shape whereby an attractive package results.

Second, to provide a wrapping machine having improved means for associating a card and an article to be wrapped with a wrapper.

Third, to provide a wrapping machine of the type having reciprocating elevator and folders associated therewith, said elevator having novel provisions for producing a regularly shaped package.

Fourth, to provide a wrapping machine of the type described having novel provisions in the form of a flight conveyor for transporting wrapped articles therefrom.

Fifth, to provide a wrapping machine of the type embodying a reciprocating vertically traveling elevator and having means for supporting a partially draped package in elevated position prior to operation of further folding instrumentalities.

Sixth, to provide a wrapping machine of the type described having improved bottom and side folding means for a partially draped wrapper.

Seventh, to provide a wrapping machine of the type described having improved means associated therewith for feeding wrapping paper at variably controllable speeds.

Eighth, to provide a machine of the type described having photoelectrically controlled means for feeding wrapping material and auxiliary means associated with such feeding means whereby the same may be employed in case a web of wrapper material is utilized which is not provided with the usual markings or spots to be viewed by the photoelectric control means.

Ninth, to provide a web feeding means characterized by improved provisions for feeding the web at different speeds as desired.

Tenth, to provide a web feeding means of the type described having novel provisions in the form of pairs of pulleys of different diameters and belts loosely associated therewith and further novel provision in the form of selectively operable belt tightening means to render the said pairs of pulleys and belts associated therewith operative at will.

Eleventh, to provide wrapper feeding and cutting mechanism for a wrapping machine which is actuatable by photoelectric means either

in the case where a web bearing viewing spots or where a plain web is employed.

Twelfth, to provide a novel web feeding and cutting mechanism particularly devised for use in a wrapping machine.

Thirteenth, to provide a method of forming a regularly shaped package for irregularly shaped objects.

Further objects relating to details and economies of my invention will definitely appear from the description to follow. The invention is defined in the claims.

A structure embodying the features of my invention is illustrated in the accompanying drawings, wherein:

Fig. 1 is a top plan view of my machine.

Fig. 2 is an enlarged fragmentary view in elevation, partially broken away and in vertical section to illustrate details of my machine and the manner of operation of the same.

Fig. 3 is an enlarged fragmentary view partially in section at right angles to Fig. 2, illustrating the wrapper feeding and cutting instrumentalities and controlling and actuating mechanisms therefor.

Fig. 4 is a fragmentary view partially in vertical section, further illustrating the details shown in Fig. 3.

Fig. 5 is a fragmentary view partially in vertical section, illustrating details of the elevator and side and end folding means and bottom folding means associated therewith to effect folding of the wrapper around an article of irregular outline.

Fig. 6 is an enlarged fragmentary view in vertical section illustrating the final folding instrumentalities of my machine.

Fig. 7 is an enlarged fragmentary view in transverse section similar to Fig. 5, illustrating the parts in a succeeding position.

Fig. 8 is a perspective view illustrating the side and end folding instrumentalities associated with the reciprocating elevator of the machine of my invention.

Fig. 9 is a fragmentary enlarged view partially in section, illustrating the wrapper feeding and gumming means employed in my machine.

Figs. 10 through 14 are perspective views illustrating the steps of the method of associating a wrapper with a card and article to be wrapped to form the completed package, as performed by the present machine.

This invention relates, generally speaking, to a machine for wrapping an irregularly shaped article, as, for instance, a bar of candy of the type commonly found in confectioneries, drug

stores, groceries, etc. Such articles have heretofore been wrapped with no attention paid to nor provisions made for shaping the wrapper in definite predetermined form relative to the article. On the contrary, the article itself has served as a former for the wrapper to be draped therearound, with the result that the wrapper is likely to adhere to the article if the latter is of a sticky nature as is generally the case. This detracts from the attractiveness of the completed package and of the product when the wrapper is removed.

Generally speaking, it is my object to remedy this condition by an improved machine which is provided with a reciprocating elevator having side guides thereon at either side of an article elevated thereby, which guides engage a wrapper blank interposed in the path of the article being elevated. The result is that the wrapper is neatly folded at right angles to its upper edge across the said side guides, which serve to impart an initial crease to the wrapper. It being elevated, the partially draped wrapper passes stationary side and end folding instrumentalities and at the uppermost point in its elevation the side and end bottom folding operations are performed thereon.

An important feature of my invention lies in the fact that I initially place a card or stiff sheet in the conveyor pockets which are employed to transport the articles to the elevator prior to wrapping, the said cards or sheets being so placed by suitable mechanism, after which the articles of irregular shape or outline are deposited on the cards by an operator or otherwise as may be desired. The aforesaid card or sheet provides a folding edge for the side and end bottom folding operations above described and materially contributes to the production of a regularly shaped package for the irregularly shaped articles.

Further specific improvements characterize my invention and have been referred to in the foregoing statements of invention. They will be more particularly described and pointed out in the specification to follow, as will the broader aspects of the invention.

Referring to the drawings, reference numeral 1 indicates the frame or base of my machine which is made of a suitable casting and provided with a flat table 2. The frame has journaled therein various shafts for actuating the folding and other instrumentalities, to be hereafter more particularly described, and in view of the fact that certain of the said shafts and driving means are conventional in nature and do not of themselves form a part of my invention, specific reference will be made only to those details germane to the invention.

Referring to Fig. 2, I provide a chain feed conveyor 3 which is trained around sprockets 4, 5 suitably journaled on shafts 6, 7 carried by the frame and around a further sprocket (not shown) rotatably carried on a spindle 8 (Fig. 1). The conveyor carries a series of pockets or compartments 9 of a size sufficient to receive a card or stiff sheet 10 and an irregularly shaped piece or bar of candy or other substance 11. The bottoms of pockets 9 are recessed at 12 for a purpose to be described. A chain tightening sprocket 13 mounted on an arm 14 pivotally carried by the frame 1 at 15 bears against the lower reach of conveyor 3 and permits the tension of the same to be adjusted at will.

The conveyor, in passing around the sprocket 75 on the spindle 8, receives a suitable rectangular

card or stiff sheet 10 from a card feeding mechanism generally designated 16, which latter is actuated to deposit a card in each pocket through a link 17 connected at one end to a suitable drive means synchronized with the rest of the machine.

Conveyor 3 is given an intermittent movement during the rest periods of which the card feeding, as well as certain of the folding operations to be hereinafter described, are performed. In order to advance the conveyor intermittently, I employ an arm or lever 171 pivoted on shaft 7 and connected through a one-way clutch or ratchet (not shown) to sprocket 5. Arm 171 is pivotally connected to a rock lever 18 medially journaled in frame 1 at 19, by a link 20. At its opposite end, lever 18 is pivotally connected to a connecting rod 21 reciprocated by suitable means (not shown) to oscillate lever 18. On the counterclockwise portion of such movement, arm 17 is rocked through a predetermined number of degrees and accordingly advances chain conveyor 3 a predetermined distance. However, on the opposite stroke of rod 21, the conveyor remains at rest.

In such manner, pockets or compartments 9 successively advance and come to rest beneath an opening 22 in table 2. In vertical alignment with opening 22 and the pocket which may be disposed therebeneath, I mount a vertical folding chute or way 23 consisting of side folding plates 24, 25 and end folding plates 26 secured to the said side folder plates in proper relation to shape the side and end folds of a wrapper around an article being elevated or translated past the plates by mechanism to be hereinafter described. The elevating mechanism or vertical ram (see Figs. 2, 5, and 7) includes a block 27 to which a link 28 is pivotally connected, the link in turn being pivotally connected to a crank arm 29 on the cross shaft 30 and adapted to be actuated thereby, thus causing block 27 and the parts carried by or connected thereto to be intermittently raised and lowered. The block has secured at its ends a pair of bars 31 terminating in outwardly directed fingers or lugs 32, which lugs are adapted to pass through the recesses 12 provided for that purpose in the bottom of conveyor pockets 9 and in passing therethrough to engage card 10 and the article 11 thereon to elevate the same past a wrapper 33 which has been previously placed in operative position over opening 22 by wrapper feed means to be hereinafter more particularly described.

I will now describe my further provisions in addition to card 10 for forming a rectangular and regularly shaped package for the irregularly shaped article 11. Such provisions consist of a pair of wrapping guide blades 34 secured to arms 31 below the lugs 32. These blades extend upwardly beyond the upper surface of lugs 32 a distance determined by the desired height of the package to be wrapped or by the size of the articles. The said blades initially engage the lower side of wrapper 33 on the upward stroke of the elevator and support the wrapper in its travel past end and side folders 24, 25, 26, imparting an initial crease thereto and spacing the wrapper slightly above the top of the article. Of course, card 10 is simultaneously engaged and elevated by lugs 32. Manifestly, the blades 34 are likewise of proper width to shape the wrapper and preferably correspond in width to the card 10 to space the wrapper vertically at the sides of the article.

In Figs. 10 to 14, the successive steps of folding wrapper 33 are illustrated. In initial position, it lies flat over opening 22 in the form illustrated in Fig. 10. Upon being engaged by wrapping 5 guide blades 34 and elevated past the lowermost edges of side folders 24, 25, the wrapper is draped as illustrated in Fig. 11. The rising, partially draped article now passes end folders 26, which act to first fold the wrapper downwardly at the 10 ends thereof, then to fold the longitudinally extending gussets 35 inwardly toward each other in overlapping relation as illustrated in Fig. 12. At this stage in the wrapping procedure, the article 11, card 10, and wrapper 33 have reached 15 the uppermost limit of the elevator's travel. Next to act are the end folding blades 36.

End folding blades 36 are of width corresponding approximately to the width of the completed 20 package and slide through openings 37 formed in end folder plates 26 to receive the same. However, prior to folding of the end bottom flaps, a 25 sustaining member or support 38 has been raised into operative position underneath card 10 in the manner illustrated in Fig. 7 to support the article, card and wrapper while the elevator and blades 34 are withdrawn on the downward stroke. Support 38 is carried on a hook-shaped lever 39 secured to a pin 40 (see Fig. 2) pivotally mounted 30 on a suitable standard 41 on table 2. Pin 40 also carries a lever 42 adapted to be oscillated periodically by a link or rod 43 extending vertically downward and which is reciprocated by suitably synchronized means to effect oscillation of lever 39. Accordingly, the draped article and card are 35 supported by member 38 during the time after the elevator has receded and prior to the action of horizontally sliding end folding blades 36. The various actuating instrumentalities for elevator arms 31, support 38 and folders 36 are suitably 40 synchronized to act in the relation described.

The end folding blades 36 heretofore referred to are carried by blocks 44 to which the links 45 are pivotally connected, which links are each pivoted to the opposite ends of a rocker 46 adapted 45 to be oscillated by a lever 47 and a connecting rod or link 48, link 48 being actuated in synchronized relation to other parts by suitable instrumentalities not necessary to specifically describe. Being positioned at one side of the folding 50 blades, it will be apparent that oscillation of rocker 46 causes blades 36 to simultaneously advance and retract, depending upon the direction of oscillation, and to fold the overlapped ends of the wrapper inwardly around the bottom of card 55 10 in the manner illustrated in Figs. 7 and 13.

The next step in the folding procedure consists of the folding inwardly of the downwardly extending side flap 49, which step is effected by folding blade 50 (see Figs. 2 and 6). I prefer to 60 advance blade 50 inwardly and at the same time impart a pivotal movement thereto in order to fold flap 49 more perfectly against the bottom of the card. To this end, blade 50 is pivoted on a lug 51 carried for horizontal movement on a 65 reciprocable slide 52. Slide 52 is guided in a stationary way 53 suitably mounted on a standard 54 carried on table 2. At its free end, blade 50 is connected to a bent spring element 55 extending lengthwise of the slide and at the opposite end 70 of the spring element the same is connected to a member on the slide by a coil spring 56. Element 55 passes beneath a roller 57 journaled in the side of slide way 53, the element being bent upwardly at 58, 59 to form cam portions engageable respectively with the forward end of the slide way 53

and with roller 57 on retraction and advance of the slide.

Slide 52 is periodically reciprocated toward the draped article to fold flap 49 beneath the same by means including a lever 60 pivoted to standard 54 at 61, a connecting rod 62 pivoted to lever 60 and driven in timed relation to the other folding mechanisms above described, and further conventional linkage connecting lever 60 to the slide whereby oscillation of the lever reciprocates the 10 slide. Inward or advance movement of slide 52 causes blade 50 to engage the flap 49 somewhat below the card 10, the blade passing through an opening 63 provided in side folding plate 25 to receive the same. When the flap 49 is partially 15 folded inwardly, the bent or cam portion 59 at the rear of element 55 engages roller 57 causing the spring 56 to be tensioned and lowering the rear end of the element. Likewise, the forward cam portion 58 leaves the forward end of the 20 slide way 53 and is elevated to raise and pivot folding blade 50, thus swinging the flap into horizontal relationship with card 10. In normal withdrawn position, the bent or cam portion 58 is engaged by the forward end of slide way 53 to 25 pull the same and blade 50 to which it is attached downwardly into the position shown in Fig. 2. The advanced horizontally disposed final folding position of blade 50 is illustrated in Fig. 6.

Simultaneous with the advance of slide 52, a 30 resilient plunger 64 slidably mounted in lug 51 and a further lug 65 on the slide way is pressed against the side of the draped wrapper to hold the same in place during the folding of flap 49. 35 A coil spring 66 encircling plunger 64 causes the latter to resiliently engage the partially draped package for this purpose.

At this time, only the depending side flap 67 remains to be folded into horizontal position beneath flap 49 and into engagement with an adhesive spot or line 68 placed thereon by mechanism to be hereinafter described. The final folding 40 operation is performed by the following mechanism. A chain discharge conveyor 69 is trained around sprockets 70 mounted on a pair of shafts 45 71, one of which shafts also has a pulley 72 thereon. The said pulley furnishes a drive to the shaft through a belt 73 which passes around and is driven by a further pulley 74. Pulley 74 is suitably driven intermittently by mechanism synchronized with the other operating parts of the machine and which need not be particularly 50 described.

Conveyor 69 has a plurality of flights 75 thereon, each of which carries a package engaging 55 member 76 adapted to come to rest adjacent the folding way 23 while an article is draped and partially folded in the manner heretofore described. Each flight likewise carries a coil spring 77 adapted to bear on the upper side of the partially wrapped package as illustrated in Fig. 2 and to assist in maintaining the partially draped wrapper in desired position during the folding of the end and side bottom flaps. Flap 49 having 60 been folded horizontally as described, and while side bottom folder 50 and plunger 64 are still in engagement with the package, conveyor 65 69 moves forwardly, pushing the package past a finger 78 pivoted at 79 adjacent the upper edge of plate 24. Forward motion of the package as 70 described causes finger 78 to be rocked and the depending flap 67 to be rotated into horizontal position. At the same time finger 78, on being swung as described, bridges the gap between the pivot point 79 and the adjacent portion of a dis- 75

charge table 81. Subsequently, the package, still resiliently pressed downwardly by spring 17, passes onto belt conveyors 82 and over a sealing element 83 designed to effect a better adhesion of 5 the flaps 49, 67, and outwardly of the machine.

The folding plates 24, 25, 26 are all suitably supported on table 2 and provisions preferably made whereby the relative position thereof may be altered at will according to the size of the 10 article being handled.

The web feeding, gumming and cutting instrumentalities together with the means for actuating and controlling the same constitute important features of my invention, being designed 15 to unfailingly feed a length of wrapping material, to apply the spot or line of adhesive 68, to cut off from the web a sheet of desired length, and to forward the same over folding opening 22. Said provisions are particularly illustrated 20 in Figs. 3, 4, and 9, to which attention is directed.

A supply roll of wrapping paper or other web material 84 is suitably supported on arms 85 (see Fig. 1), the said material preferably bearing 25 a series of marks 86 adapted to control the actuation of photoelectric viewing means to be hereinafter described. However, the said marks need not be provided, as my machine is characterized by auxiliary control means for the photoelectric viewing means as will also be hereinafter 30 described.

The web 84 is fed downwardly from the supply roll around a suitable tensioning roll (not shown), then upwardly and to the right as viewed in Fig. 3 around an idler (not shown), thence 35 to the left around a feed roll 87 which is intermittently driven by mechanism to be hereinafter described. The feed roll is journaled in brackets 88 suitably carried by frame 2. The web passes 40 between feed roll 87 and a further feeding roll generally indicated 89 made up of a plurality of lengths 90 of suitable friction material adapted 45 to engage the web against roll 87 and feed the same forwardly, the gaps between the lengths serving to prevent smearing of the adhesive spot 45 or stripe 68.

The said spot or stripe is applied to the web as it passes around the lower side of roll 87 by mechanism which is illustrated in Fig. 9. Said mechanism consists of a disk 91 having a 50 gum applying offset 92 adapted to contact the web. Disk 91 is carried by a collar 93 splined to a stub shaft 94 suitably supported for rotation adjacent and beneath roller 87. Disk 91 travels in an adhesive pot or container 95 suitably 55 mounted on the frame of the machine, the collar 93 having an annular groove adapted to receive the wall 96 of the adhesive pot to restrain the collar and disk from excessive axial movement. Chain 97 is driven to rotate shaft 94 60 from a suitable rotating part of the machine.

Rollers 87, 89 are driven to advance the web a predetermined distance each time they are rotated and to feed a predetermined length of the web between the cutting rollers 98, 99 immediately to the rear of the feeding rollers whereby the said cutting rollers will sever a proper length from the web at each cutting operation. The cutting rollers are driven continuously 65 though a chain 100 passing around the sprocket 101 secured to the upper of the cutting rollers 99 and around a further sprocket 102 carried by a shaft 103 which latter shaft is continuously 70 driven in suitable manner not illustrated. The intermittent feed of the proper length of web 75 between the bite of the rollers 98, 99 is accom-

plished by photoelectric viewing means as follows.

Reference numeral 104 in general indicates photoelectric viewing means of suitable type secured to a cross bar 105 on the machine and focused to view the marks 86 as they are advanced across the viewing field. The photoelectric viewing means is suitably connected through an interrupter switch generally indicated 105' to a selenoid or relay 106. Energization of the coil of the latter causes a lever 107 pivoted at 108 to be attracted and interpose a stop 109 in the path of a clutch arm 110 governing the rotation of a shaft 135 and thus disconnecting the driving means for feed rolls 87, 89 and halting the feed 15 of the web. The feed rolls are driven from shaft 135 by an adjustable belt transmission as will be hereinafter particularly described.

Obviously some means must be provided for 20 again starting the feed of the web after a sufficient time interval. To perform such function, I employ a cam 111 fixed to the shaft of cutter roll 99, said cam being adapted to elevate and lower a follower roller 112 on a pivoted arm 113 journaled at 114. Oscillation of arm 113 is effective to separate a contact 115 connected by a strap 116 to the arm from a stationary contact 117 fixedly mounted on the framework of the machine. Obviously, this breaks the circuit between the photoelectric cell 104 and the relay 106 30 and under the influence of a suitable spring or other means (not shown) lever 107 is released and stop lug 109 removed from engagement with clutch arm 110 causing shaft 135 to be rotated again and the web feed to be initiated and to continue until a further mark 86 passes the photoelectric cell.

The electrical connections between cell 104, switch 105', and relay 106 are entirely conventional and it is not considered necessary to illustrate the same.

In the event that it is desired to utilize wrapping paper having nothing corresponding to the marks 86 printed thereon or a plain paper or "Cellophane," I have provided auxiliary means 45 governed by cam 111 and associated with the photoelectric viewing means to cause a definite length of web material to be fed on each operation of the feed rolls. Said means consists of an arm 118 pivoted at 119 and pivotally connected to arm 113 through a link 120. Arm 118 has pivoted at its outer end a tongue 121 pivotally connected to the yoke 122 of an adjustable link 123, the length of which may be controlled by the manipulation of a set screw 124. A further 55 yoke 125 at the other end of link 123 has pivoted thereto an elongated arm 126 fulcrumed at 127 and adapted to be intermittently brought into and out of the viewing field of photoelectric cell 104. When arm 126 is brought from its dotted 60 line position in Fig. 9 to the full line position, it causes the field to be darkened and an impulse to originate in the photoelectric cell. Therefore, it will be seen that arm 126 in effect replaces marks 86 on the web in their function of causing 65 an impulse to originate in the photoelectric cell at definitely timed intervals and renders the use of such marks unnecessary. However, when a web having the marks imprinted thereon is employed, the auxiliary means may be disconnected in a number of ways, either by loosening set screw 124 and disconnecting link 123 or by 70 removing arm 126 entirely as illustrated in Fig. 3.

By the foregoing mechanism, the web is caused 75 to travel intermittently a predetermined distance

between each severing operation performed by cutting rolls 98, 99. The feed rolls 87, 89 carry meshing gears 128, 129, respectively, and gear 128' meshing with a gear 128" on shaft 130, which is rotatably carried by a bracket 131. Shaft 130 also has secured thereto a sprocket 132 around which a chain 133 is trained. Chain 133 further passes around a sprocket on shaft 134 and is driven thereby. Shaft 134 and the sprocket thereon are driven from a clutch controlled shaft 135 above referred to through a belt transmission generally indicated 136, the said belt transmission causing shaft 134 to be rotated each time the clutch arm is released by stop lug 109 as described above. Lug or stop 109 and arm 110 actuate a suitable overrunning or other type of clutch (not shown) to cause shaft 135 to be disconnected from its source of power.

The belt transmission 136 is a novel arrangement which I have devised to enable feed rollers 87, 89 to be selectively driven at different speeds under the control of an operator. Said transmission is illustrated in Figs. 3 and 4 and consists of a pair of pulleys 137, 138 of different diameters on shaft 135, said pulleys being in alignment with further pulleys 139 on shaft 134. Belts 140, 141 pass around pulleys 137, 138 respectively and their aligned pulleys 139, the said belts being loosely associated with their corresponding pulleys whereby when not subjected to any tightening action, there is insufficient traction between the belts and pulleys to cause any driving action.

The invention comprehends means to selectively engage belt 140 or belt 141 with their corresponding pulleys, whereby one or the other of pulleys 139 may be actuated and as a result the rollers 87, 89 may be driven at different speeds. The said means consist of a pair of belt engaging rollers 142, 143. As illustrated, roller 142 is adapted to be engaged with belt 140 to take up slack therein and when roller 142 is disengaged from its belt roller 143 is adapted to be brought into tightening relation with belt 141. Rollers 142, 143 are journaled on a bar 144 mounted in fixed relation to an arm 145 which is pivoted at 135. Arm 145 is actuatable by a rod 146 pivotally connected thereto. Accordingly, depending upon the actuation of a rod 146, motion is transmitted to shaft 134 through pulley 138 or pulley 137 and as a result rollers 87, 89 are rotated to advance the web more or less rapidly.

The movement of rod 146 is derived from a cam 147 having a track 148 receiving a follower 149 on the rod. The free end of the said rod is forked at 150 to receive the cam drive shaft 151, which may be any suitable synchronized rotating shaft.

Inspection of Figs. 3 and 4 shows my belt transmission as being mounted on the exterior of the machine in an easily available position in case it is desired to make changes or adjustments therein. Shafts 134, 135 are journaled in a strap or side frame 152 secured to the exterior of the machine frame.

Upon being severed by cutter rolls 98, 99, the sheet of wrapper material is received between belts 153 and rollers 154 bearing thereon (see Figs. 1 and 2) and the severed sheets are transported by the said belts to position over opening 22, the belts being synchronized by suitable means with the other operating instrumentalities of my machine.

I have illustrated and described my improvements in an embodiment which is very practical.

I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. In a wrapping machine for irregular articles, means for intermittently feeding articles and cards to initial wrapping position, means for placing a series of cards on said feeding means, said articles to be wrapped being thereafter placed on said cards and fed therewith to the initial wrapping position, means for feeding a wrapper to position above the article to be wrapped at said initial wrapping position, mechanism for thereafter folding the wrapper about the top and sides of the article to be wrapped, comprising a vertical folding way having side and end wrapper folder plates, and a reciprocating elevator adapted to engage said card and elevate the article and card through said way, said elevator having folding guide members thereon extending above the article on the elevator to engage the wrapper and elevate the wrapper with the article through the folding way and past said plates, said guide members spacing the wrapper from the article during folding whereby to form a regular package for said article having square edges, means to fold the ends and sides of said wrapper around the bottom of said card, and means to transport the wrapped article and card from folding position.

2. In a wrapping machine for irregular articles, means for intermittently feeding articles and cards to initial wrapping position, means for feeding a wrapper to position above the article to be wrapped at said initial wrapping position, and mechanism for thereafter folding the wrapper about the top and sides of the article to be wrapped, comprising a vertical folding way having side and end wrapper folder elements and an elevator adapted to engage said card and elevate the article and card through said way, said elevator having folding guide members thereon extending above the article on the elevator to engage the wrapper and elevate the wrapper with the article through the folding way and past the said elements, said guide members spacing the wrapper from the article during folding whereby to form a regular package for said article having square edges.

3. In a wrapping machine for irregular articles, mechanism for folding a wrapper about the top and sides of an article and a card associated therewith comprising a vertical folding way having side and end folding plates and a reciprocating elevator adapted to engage and elevate the article and card through said way, said elevator having folding guide members fixedly secured thereto and extending above the article on the elevator to engage the wrapper and elevate the wrapper with the article through said way and space the wrapper from the article during folding whereby to form a square edged package for said article.

4. In a wrapping machine for irregular articles, mechanism for folding a wrapper about an article and a card associated therewith comprising a folding way and a traveling ram adapted to engage and actuate the article and card through said way, means for disposing a wrapper in line with said way and in the path of travel of said article and card, said ram having folding guide

members fixedly secured thereto and extending in advance of the article to engage the wrapper and move the wrapper with the article through said way and space the wrapper from the article 5 during folding whereby to form a square edged package for said article.

5. A wrapping machine for wrapping pre-formed articles of irregular shape to produce packages of regular shape comprising a folding way and a reciprocating folding member adapted 10 to transport an article, a card and a wrapper for said article and card past said folding way whereby to drape said wrapper around the top, sides and ends of said article during said transportation, said member having means attached thereto 15 extending beside and in advance of the article in the direction of travel of the same during folding and adapted to initially engage the wrapper to space the wrapper from the article and 20 form square side and end folds in the wrapper at the foremost side of the article during its advance, and means for folding the wrapper around the rearmost side of the card, said card cooperating with said last named folding means 25 to space the wrapper from the article and to provide square side and end folds in the wrapper at the rearmost side of the package.

6. In a wrapping machine, in combination, 30 means to feed articles of irregular shape to be wrapped to folding position comprising an intermittently moving continuous conveyor having spaced article receiving pockets therein, means for depositing a card in each of said pockets prior to placing an article to be wrapped therein, 35 folding means comprising a vertically disposed folding way having side and end folding plates and an elevator movable past said way, said article feed means intermittently halting in line with said way and elevator, means for intermittently feeding a web of wrapping material and 40 cutting said web into sheets of desired length, means for forwarding said sheets to position above said article and in line with said way and elevator, means to reciprocate said elevator to 45 engage the card in said pocket above the elevator and to elevate the card and article thereon and the wrapper thereabove past said folding way whereby to drape the sides and ends of said wrapper about said article, said elevator having 50 spaced fingers extending in advance of said article and engaging said wrapper to space the same from the article and in conjunction with said side and end folding plates to form square side and end edges at the top of the draped wrapper, a swinging arm adapted to engage the under 55 side of the card at the end of its travel through said way to support the same during the retraction of the elevator, means for actuating said arm, and means for folding the ends and sides 60 of said wrapper around the bottom of said card, said card spacing the wrapper from the article to provide square side and end edges at the bottom of the article.

7. In a wrapping machine, in combination, 65 means to feed articles of irregular shape to be wrapped to folding position comprising a conveyor having spaced article receiving pockets therein, means for depositing a card in each of said pockets prior to placing an article to be wrapped therein, folding means comprising a vertically disposed folding way having side and end folding plates and an elevator movable past said way, said article feed means intermittently halting in line with said way and elevator, means for 70 forwarding wrapping sheets to position above

said article and in line with said way and elevator, means to reciprocate said elevator to engage the card in said pocket above the elevator and to elevate the card and article thereon and the wrapper thereabove past said folding way 5 whereby to drape the sides and ends of said wrapper about said article, said elevator having spaced fingers extending in advance of said article and engaging said wrapper to space the same from the article and in conjunction with said side 10 and end folding plates to form square side and end edges at the top of the draped wrapper, a swinging arm adapted to engage the under side of the card at the end of its travel through said way to support the same during the retraction of the elevator, means for actuating said arm, and means for folding the ends and sides of said wrapper around the bottom of said card, said card spacing the wrapper from the article to provide square side and end edges at the bottom of the 20 article.

8. In a wrapping machine, in combination, means to feed articles to be wrapped to folding position, folding means comprising a vertically disposed folding way having side and end folding plates and an elevator movable past said way, said articles being intermittently halted in line with said way and elevator, means for feeding sheets of desired length to position above said article and in line with said way and elevator, 30 means to reciprocate said elevator to elevate the article and the wrapper thereabove past said folding way whereby to drape the sides and ends of said wrapper about said article, a movable support adapted to engage the article at the end of its travel through said way to support the same during the retraction of the elevator, means for actuating said support to supporting position relative to the article, and means for folding the ends and sides of said wrapper around the bottom 40 of said article during and after retraction of the elevator.

9. In a wrapping machine, means for elevating an irregular article to be wrapped, a card lying beneath the same, and a wrapper past instrumentalities for draping the sides and ends of the wrapper around the article, said elevating means having means for engaging the wrapper in advance of the article to space the wrapper from the article and form square upper side and end edges 50 for the draped wrapper, means for folding the ends of the wrapper around and beneath the card comprising horizontally movable plates and means for periodically shifting said plates inwardly into engagement with the ends of the 55 draped wrapper, means for folding one side of the draped wrapper around and beneath the card comprising a slide, a folding plate pivoted thereto, means for periodically shifting the slide and last named plate inwardly toward the wrapper, 60 and means for pivoting the plate upwardly during said inward shifting to swing the side of the wrapper toward the bottom of the card, and means for folding the other side of the draped wrapper around and beneath the card comprising 65 means for moving the partially wrapped article transversely of said other side and a pivoted element engageable with said other side to swing the same around said card and into engagement with the bottom thereof.

10. In a wrapping machine, means for elevating an irregular article to be wrapped, a card lying beneath the same, and a wrapper past instrumentalities for draping the sides and ends of the wrapper around the article, means for folding 70

the ends of the wrapper around and beneath the card comprising horizontally movable plates and means for periodically shifting said plates inwardly into engagement with the ends of the draped wrapper, means for folding one side of the draped wrapper around and beneath the card comprising a slide, a folding plate pivoted thereto, means for periodically shifting the slide and last named plate inwardly toward the wrapper, and means for pivoting the plate upwardly during said inward shifting to swing the side of the wrapper toward the bottom of the card, and means for folding the other side of the draped wrapper around and beneath the card comprising means for moving the partially wrapped article transversely of said other side and a pivoted element engageable with said other side to swing the same around said card and into engagement with the bottom thereof.

11. In a wrapping machine, means for elevating an irregular article to be wrapped, a card lying beneath the same, and a wrapper past instrumentalities for draping the sides and ends of the wrapper around the article, means for folding one side of the draped wrapper around and beneath the card comprising a slide, a folding plate pivoted thereto, means for periodically shifting the slide and last named plate inwardly toward the wrapper, and means for pivoting the plate upwardly during said inward shifting to swing the side of the wrapper toward the bottom of the card, and means for folding the other side of the draped wrapper around and beneath the card.

12. In a wrapping machine, means for elevating an irregular article to be wrapped, a card lying beneath the same and a wrapper past instrumentalities for draping the sides and ends of the wrapper around the article, means for folding the ends of the wrapper around and beneath the card comprising horizontally movable plates and means for periodically shifting said plates inwardly into engagement with the ends of the draped wrapper, means for folding one side of the draped wrapper around and beneath the card comprising a slide, a folding plate pivoted thereto, means for periodically shifting the slide and last named plate inwardly toward the wrapper, and means for pivoting the plate upwardly during said inward shifting to swing the side of the wrapper toward the bottom of the card, and means for folding the other side of the draped wrapper around and beneath the card comprising means for moving the partially wrapped article transversely of said other side and a pivoted element engageable with said other side to swing the same around said card and into engagement with the bottom thereof.

13. In a wrapping machine, means for elevating an irregular article to be wrapped, a card lying beneath the same and a wrapper past instrumentalities for draping the sides and ends of the wrapper around the article, means for folding one side of the draped wrapper around and beneath the card comprising a slide, a folding plate pivoted thereto, means for periodically shifting the slide and last named plate inwardly toward the wrapper, and means for pivoting the plate upwardly during said inward shifting to swing the side of the wrapper toward the bottom of the card, and means for folding the other side of the draped wrapper around and beneath the card comprising means for moving the partially wrapped article transversely of said other side and a pivoted element engageable with said other side to swing the same around said card and into engagement with the bottom thereof.

14. In a wrapping machine, means for elevating an irregular article to be wrapped, a card lying beneath the same and a wrapper past instrumentalities for draping the sides and ends of the wrapper around the article, means for folding one side of the draped wrapper around and beneath the card, and means for folding the other side of the draped wrapper around and beneath the card comprising means for moving the partially wrapped article transversely of said other side and a pivoted element engageable with said other side to swing the same around said card and into engagement with the bottom thereof.

15. In a wrapping machine, means for elevating an article to be wrapped, and a wrapper past instrumentalities for draping the sides and ends of the wrapper around the article, means for folding one side of the draped wrapper around and beneath the card comprising means for moving the partially wrapped article transversely of said other side and a pivoted element engageable with said other side to swing the same around said card and into engagement with the bottom thereof.

16. In a wrapping machine, means for elevating an article to be wrapped, and a wrapper past instrumentalities for draping the sides and ends of the wrapper around the article, means for folding one side of the draped wrapper around and beneath the article comprising a slide, a plate pivoted thereto, means for periodically shifting the slide and last named plate inwardly toward the wrapper, and means for pivoting the plate upwardly during said inward shifting to swing the side of the wrapper around the bottom of the article, and means for folding the other side of the draped wrapper around and beneath the article comprising means for moving the partially wrapped article transversely of said other side and a pivoted element engageable with said other side of the wrapper to swing the same around said article and into engagement with the bottom thereof.

17. In a wrapping machine, a vertical folding way, a reciprocating elevator to transport an article to be wrapped and a wrapper therefor past said way whereby the sides and ends of the wrapper are draped around the article, means on said elevator to engage the wrapper and space the same from the article whereby to form square side and end edges at the top thereof, means adjacent the top of the way for folding the wrapper around the bottom sides and ends of the article, and means for supporting the partially draped article during the down stroke of the elevator and until further support therefor is afforded by said folding means, comprising an arm pivotally mounted adjacent the way, and means for periodically swinging the arm into operative supporting relation to the article, said way having provision for receiving the arm during said swinging movement.

18. In a wrapping machine, a vertical folding way, a reciprocating elevator to transport an article to be wrapped and a wrapper therefor past said way whereby the sides and ends of the wrapper are draped around the article, means separate from said folding means supportingly engageable with the article prior to the down stroke of the elevator for supporting the partially draped article during the down stroke of the elevator and until further support therefor is afforded by said folding means, comprising an arm pivotally mounted adjacent the way, and means for periodically swinging the arm into operative supporting relation to the article, said way having provision for receiving the arm during said swinging movement.

19. In a wrapping machine, a vertical folding way, a reciprocating elevator to transport an article to be wrapped and a wrapper therefor past said way whereby the sides and ends of the wrap-

- per are draped around the article, means adjacent the top of the way for folding the wrapper around the bottom sides and ends of the article, means separate from said folding means supportingly engageable with the article prior to the down stroke of the elevator for supporting the partially draped article during the down stroke of the elevator and until further support therefor is afforded by said folding means, and means for 10 periodically bringing said supporting means into operative supporting relation to the article.
19. In a wrapping machine, a vertical folding way, a reciprocating elevator to transport an article to be wrapped and a wrapper therefor past 15 said way whereby the sides and ends of the wrapper are draped around the article, means on said elevator to engage the wrapper and space the same from the article whereby to form square side and end edges at the top thereof, means 20 adjacent the top of the way for folding the wrapper around the bottom sides and ends of the article, means for supporting the partially draped article during the down stroke of the elevator and until further support therefor is afforded by 25 said folding means, and means for periodically bringing said supporting means into operative supporting relation to the article.
20. In a wrapping machine, a vertical folding way, a reciprocating elevator to transport an article to be wrapped and a wrapper therefor past 30 said way whereby the sides and ends of the wrapper are draped around the article, means for folding the wrapper around the bottom sides and ends of the article, and means separate from 35 said folding means supportingly engageable with the article prior to the down stroke of the elevator for supporting the partially draped article during the down stroke of the elevator.
21. In a wrapping machine, a vertical folding way, a reciprocating elevator to transport an article to be wrapped and a wrapper therefor past 40 said way whereby the sides and ends of the wrapper are draped around the article, means on said elevator to engage the wrapper and space the same from the article whereby to form square side and end edges at the top there-

of, means adjacent the top of the way for folding the wrapper around the bottom sides and ends of the article, and means for supporting the partially draped article during the down stroke of the elevator, comprising an arm pivotally mounted adjacent the way. 5

22. In a wrapping machine, a vertical folding way, a reciprocating elevator to transport an article to be wrapped and a wrapper therefor past 10 said way whereby the sides and ends of the wrapper are draped around the article, means on said elevator to engage the wrapper and space the same from the article whereby to form square side and end edges at the top thereof, means adjacent the top of the way for folding the wrapper around the bottom sides and ends of the article, and means for supporting the partially draped article during the down stroke 15 of the elevator.

23. In a wrapping machine, means for elevating an irregular article to be wrapped and a wrapper past instrumentalities for draping the sides and ends of the wrapper around the article, said elevating means having means engaging the wrapper at spaced points in advance of the article 20 to space the wrapper from the article and form square upper side and end edges for the draped wrapper as the same is elevated, periodically acting means for folding the ends of the wrapper around and beneath the article, means for 25 folding one side of the draped wrapper around and beneath the article, comprising a periodically acting folding member, a folding element pivoted thereto, means for periodically actuating said member and element inwardly toward the wrapper, means for pivoting the element upwardly during said inward actuation to shift one side of the wrapper toward the bottom of the article, means for folding the other side of the draped 30 wrapper around and beneath the article, comprising means for moving the partially wrapped article transversely, and means engageable with said other side upon said transverse movement to swing the same around said article and into engagement with the bottom thereof. 35

OSCAR SANDBERG. 45
